(57) **CLAIM**

I claim the ornamental design for a target stand, as shown and described.

DESCRIPTION

FIG. 1 is a front, left side perspective view of a target stand showing my design;

FIG. 2 is a front elevation view thereof, it being understood

that the opposite side is a mirror image of that shown;

FIG. 3 is a left side elevation view thereof, it being under-

stood that the opposite side is a mirror image of that shown;

FIG. 4 is a top plan view thereof; and,

FIG. 5 is a bottom plan view thereof.

The broken lines shown represent unclaimed subject matter and form no part of the claimed design.

1 Claim, 4 Drawing Sheets

FIG. 1

FIG. 4

FIG. 5
